UNITED STATES PATENT OFFICE.

CHARLES D. RUSSELL, OF ST. PAUL, MINNESOTA.

RAILWAY SPIKE.

1,134,160.

Specification of Letters Patent. Patented Apr. 6, 1915.

Application filed May 5, 1914. Serial No. 286,466.

To all whom it may concern:

Be it known that I, CHARLES D. RUSSELL, a citizen of the United States, residing at St. Paul, in the county of Ramsey and State of Minnesota, have invented certain new and useful Improvements in Railway-Spikes, of which the following is a specification.

This invention relates to railway spikes and has for its primary object to provide a device of this character constructed in such a manner as to so engage the tie when embedded therein that vertical movement of the spike may be prevented, which might otherwise be brought about through the severe jars or strains to which such spikes are subjected.

The invention has as a further object to provide in a spike thus formed a construction which will also so engage the tie as to prevent lateral movement of the spike therein. And a still further object of the invention is to provide a spike which will be simple in construction and which may thus be readily manufactured and which at the same time will be very efficient in operation.

With these and other objects in view my invention will be more fully described, illustrated in the accompanying drawings, and then specifically pointed out in the claims which are attached to and form a part of this application.

In the accompanying drawings:—Figure 1 is a perspective view showing my improved spike in operative position partly embedded within a railway tie, the railway tie and rail being conventionally illustrated, Fig. 2 is an elevation showing one side of the spike, Fig. 3 is a fragmentary sectional view on an enlarged scale taken on the line 3—3 of Fig. 2, and Fig. 4 is a transverse sectional view taken through the spike when embedded within the tie and especially showing the manner in which the spike is engaged by the tie.

Corresponding and like parts are referred to in the following description and indicated in all the views of the drawings by the same reference characters.

My improved spike may be formed of any suitable metal and includes a shank 10 upon one extremity of which is formed a head 11, the opposite extremity of the shank being cut away to provide a driving point 12, arranged in longitudinal relation to the head.

The shank 10 is substantially rectangular

in cross-section and immediately adjacent the head 11, the several sides of the spike are formed with flat straight faces 13. When the spike is embedded within the tie, 60 one of said faces is designed to contact with the adjacent edge of the flange of the rail to thus form a solid abutment therefor, while the face upon the opposite side of the spike provides an unobstructed flat bearing 65 surface for the adjacent portion of the tie, such construction of the spike acting to prevent lateral movement thereof when in practical use and thus overcoming the spreading of the rails. 70

At the free extremities of the faces 13, the sides of the shank 10 are cut away to provide longitudinally extending concave faces or channels 14 which open at their lower extremities upon the adjacent beveled faces of 75 the spike which provide the driving point 12. The side edges 15 of the concave faces 14 are disposed inwardly of the adjacent side edges of each side of the spike as shown, said concave faces being disposed medially 80 of the sides of the shank.

Formed in each concave face 14 upon the front and rear sides of the spike is a series of longitudinally spaced transversely extending parallel grooves 16, the channels 85 upon the other sides of the spike being left smooth for a reason which will be presently explained. The side walls of the grooves 16 provide transversely curved shoulders 17 and it will be observed that the end walls of 90 each of said grooves form undercut or inclined shoulders 18 arranged adjacent the side edges of the adjacent faces 14.

As is well known, the grain of the wood of a railway tie as ordinarily constructed, 95 runs lengthwise thereof and in forming the series of grooves 16 in the front and rear faces of the spike, it will be seen that said grooves are so arranged as to engage the severed ends of the fibers of the tie caused 100 by driving the spike into the tie, while the unbroken fibers of the tie adjacent the oppositely arranged side faces of the spike will expand into the smooth concave faces thereof. Since the wood of the tie under ordinary circumstances will have the greatest tendency to swell or expand with the grain thereof, the grooves 16 are arranged upon the side faces of the spike against which the greatest expansion of the tie will occur and owing to the relatively small lateral expansion of the wood, the oppositely arranged 110

side faces of the spike are left smooth, thus reducing the expense of manufacturing.

As will be readily obvious, when the spike is embedded within a tie, the wood fibers thereof will expand into the concave faces 14 and will particularly expand to engage the front and rear faces of the spike, and thus enter the grooves 16 to be engaged by the curved shoulders 18 formed by the side 10 walls of said grooves. Said shoulders being arranged transversely of the spike, will therefore, engage the tie to prevent the vertical movement of the spike, and it will also be clear that the adjacent portions of the 15 tie expanded into the grooves 16 will also expand to be engaged by the oppositely inclined shoulders 18 formed by the end walls of each of said grooves. This is best shown in Fig. 4 of the drawings and it will be observed that said shoulders are so arranged 20 as to prevent transverse movement of the spike.

I thus provide a construction wherein the spike is held, when in engagement with the 25 tie, both as against vertical and transverse movement, and while I have shown the longitudinally spaced grooves 16 as extending the entire length of the adjacent concave faces 14 of the spike, still, it is to be understood that I do not wish to limit myself to any particular number of said grooves nor to the relative spacing thereof.

From the above description in connection with the accompanying drawings, it will be 30 seen that I provide a very simple and efficient structure for the purpose set forth, such as may be readily manufactured and which will be found highly practical in actual use.

40 Having thus described my invention, what I claim and desire to secure by Letters Patent is:—

1. A railway spike including a shank having a head formed thereon and being provided with a driving point, said shank being formed with adjacent side faces having longitudinally extending channels formed therein, one of said channels being substantially smooth and the other of said channels 50 being provided with a plurality of transversely extending shoulders and oppositely inclined converging shoulders.

2. A railway spike including a shank having a head formed thereon and being provided with a driving point, said shank being substantially rectangular in cross section and formed with flat faces adjacent the head thereof, there being longitudinally extending channels medially formed in the 60 sides of the shank at the adjacent extremities of said flat faces, oppositely disposed channels being arranged in pairs, one pair

of channels having a series of longitudinally spaced transversely extending parallel grooves medially formed therein, the side 65 walls of each of said grooves providing longitudinally curved shoulders and the end walls thereof providing oppositely inclined converging shoulders at the extremities of said first mentioned shoulders, the other pair 70 of channels of the spike being substantially smooth.

3. A railway spike including a shank having a head formed thereon and provided with a driving point, said shank having a 75 transversely arranged shoulder formed thereon continuously curved from end to end and provided with oppositely inclined shoulders at the extremities of said first mentioned shoulder, said last mentioned 80 shoulders inclining inwardly toward each other and in a direction over said first mentioned shoulder.

4. A railway spike including a shank having a head formed thereon and provided 85 with a driving point, said shank having a groove formed therein defining transversely arranged shoulders upon one side of the shank, said shoulders being continuously curved from end to end and said shank having 90 oppositely inclined shoulders formed thereon at the extremities of said first mentioned shoulders, said last mentioned shoulders inclining inwardly toward each other and in a direction over said groove and over 95 said first mentioned shoulders.

5. A railway spike including a shank having a head formed thereon and provided with a driving point, said shank having a 100 transversely arranged shoulder formed thereon continuously curved from end to end and having outwardly converging oppositely inclined shoulders formed thereon at the extremities of said first mentioned shoulder.

105 6. A railway spike including a shank having a head formed thereon and provided with a driving point, said shank being formed with a longitudinally extending channel upon one side thereof and having a 110 transversely disposed groove formed in said channel, the said groove defining shoulders continuously curved from end to end and also defining oppositely inclined shoulders at the extremities of said first mentioned 115 shoulders, the said last mentioned shoulders inclining inwardly toward each other and in a direction over said groove.

In testimony whereof I affix my signature in presence of two witnesses.

CHARLES D. RUSSELL. [L.S.]
